UNITED STATES PATENT OFFICE.

EDWIN B. KENNGOTT, OF BUFFALO, NEW YORK.

DESIGN FOR A DOLL.

Application filed February 3, 1925. Serial No. 12,250. Term of patent 3½ years.

To all whom it may concern:

Be it known that I, EDWIN B. KENNGOTT, a citizen of the United States, residing at Buffalo, in the county of Erie and State of New York, have invented a new, original, and ornamental Design for Doll, of which the following is a specification, reference being had to the accompanying drawing, forming part thereof.

I claim:

The ornamental design for a doll, as shown.

EDWIN B. KENNGOTT.
